UNITED STATES PATENT OFFICE

W. BARTLETT JONES, OF CHICAGO, ILLINOIS

ELECTRICAL PHONOGRAPH PICK-UP AND APPARATUS

Application filed January 25, 1930, Serial No. 423,351. Renewed January 9, 1932.

The present invention relates to electrical phonographs and to pick-up devices for phonograph records, having particular reference to a device which is capable of picking up vibrations from records which are cut laterally and from records which are cut vertically.

The pick-up is not limited to an alternative use with the two types of records but is so constructed that it has in addition the ability to pick up with one stylus, two different records in one groove, one of which may be cut laterally and the other of which may be cut vertically. The entire device may combine the two picked up records when they are intelligibly related. Such records may be coordinated instrumental and vocal numbers or otherwise related as described in U. S. patent to Waters No. 1,520,378, Emerson No. 1,522,949 and Heck No. 1,842,442. The records may also be differently phased effects of the same sound as described and claimed in my copending applications Ser. No. 183,414, filed April 13, 1927 and Serial Number 311,488, filed Oct. 10, 1928. Reference is also made to copending application Ser. No. 326,023, filed December 14, 1928 which is in nature generic to the others.

The present application is generic to the pick-up device itself and specific to certain features previously disclosed in some of the above applications.

The primary object of the invention is the provision of a device having a single stylus capable of picking up two separate records in the same track with a single track-follower, or stylus, and to combine, or to separate the two records for reproduction.

A particular object is to provide two electrical pick-up devices in combination with a common stylus.

A further object is to provide two electrical pick-up devices for two records with a control connection means, whereby the two records, in the form of current may be varied in actual and relative intensity, and presented either separately at different times or simultaneously, or combined simultaneously.

Various other objects and advantages of

the invention will be apparent from the following description of one form of the invention as it is shown in the accompanying drawings, in which

Fig. 1 is a plan view of an electric phonograph table.

Fig. 2 is a detail front elevation of the electrical pick-up device showing a record in cross section.

Fig. 3 is a plan view of the device in Fig. 2.

Fig. 4 is an end view of the device coupled with a diagrammatic representation of electric connections.

In the drawings the numeral 8 indicates a phonograph base having a turntable 9. 10 indicates a spiral groove record having a vertical sound track 11 and a horizontal sound track 12 combined in the same groove. A groove-follower is provided such as a needle 13 mounted in the socket means 14 which is carried on a block having the form of a cube 15. The phonograph 9 carrying the device has a swinging arm 16 with a lateral extension 17. From the lateral extension 17 a resilient or springy projection 18 extends parallel to the record and more or less in the direction of the tangents to the sound groove. The block 15 is carried by the member 18 so that it is free to vibrate laterally and vertically. Above the block 15 is a microphone element 19 with a ball contact 20 resting on the flat top of the cube. The microphone is merely illustrative of many types of electrical devices sensitive to vibrations, and may be understood here to be of the carbon granule type. One lateral face of the cube has a similarly contacting microphone element 21 and ball contact 22. Each vibration may thus be recorded independently of the other. The microphones are mounted on a rigid member 23 which is carried by the extension 17. This type of device is represented generally in Fig. 1 by the numeral 24.

The device and the double record are particularly useful for reproducing phased versions of the same sounds, such as binaural effects. Weir, in Patent Number 1,508,432 discloses a binaural phonograph system in which separate records are synchronized and picked up by separate styli. In binaural sys-

tems a phase deviation of about .00023 seconds may indicate an angular change as great as 90°. And where two needles are employed for synchronized records, travelling about 80 inches per second relative to the record, it is seen that there must be a constant accurate adjustment of the two needles to record, to reproduce and to maintain the effect. An error of .01 of an inch in the required relative positions of the needles on two records would destroy the true effect. The present invention eliminates delicate mechanism and all possibility of mechanical defects using two needles.

15 The device may be employed with ear phones as disclosed by Weir to secure the binaural effects. It may also be employed with separated loud type speakers as disclosed in the applicant's copending applications above named, or in accordance with the disclosure of German Patent 360,719, showing another way of presenting binaural effects. In each instance two receiving circuits are required, one from each side of the pick-up device. In Fig. 1, electrical plugs 25 and 26 are indicated for attachment of such means.

However, the invention is not limited to the binaural systems, and it may be used with 30 any other two records, especially intelligibly related ones. Extra-binaurally related records of the same sounds may be employed, and the later phase of one sound appears as a reflection of the earlier, giving increased 35 quality to the combination. Extra-binaural versions may be used to separate sources as disclosed in my copending application Ser. No. 210,629, filed August 4, 1927. As an example of other intelligibly co-ordinated effects there is cited a complete selection which may be divided into two portions, for example a singer on one system and the accompaniment on the other, so that each may be played and controlled as desired by the auditor.

The present invention may also be employed in the phonographic field to record and reproduce dialogue, dual combat, and the like. For dialogue, two loud speakers receiving different recorded, yet intelligibly coordinated, conversations, may be placed at 50 separate points and appear to converse with each other, all from one record. Games such as chess, may be reproduced with action by 55 providing participants with head phones through which each receives independent and intelligibly coordinated instructions how to act.

60 The two records may contain vibrations according to one or more other variables than sound, such as light or television records which it is desired to coordinate with another record.

65 In order to make the device flexible for

various applications other features are provided.

In Fig. 4 the reproducer for the two effect record is shown as having its independent circuits 30 and 31, from the microphone elements 19 and 21 respectively, connected into a circuit control box 32. Variable controls 33 and 34 are provided for each circuit to vary the intensity of the tone in each circuit. Terminals 35 and 36 may be connected by 75 suitable mechanism (not shown) to permit optional connection to one or two reproducers. The use of one reproducer 37 is particularly 80 advantageous, and is now found in many phonographs. Both effects may be combined in the one reproducer, or each may be reproduced individually in two reproducers 37 and 38. A vocal effect on one side and an instrumental effect on the other may be thus played 85 separately or in combination, at any tone volume and at any ratio of tone volume when combined.

Various modifications in the invention may be made within the skill of the art. The microphone elements may be condenser types 90 or carbon granule types, or diaphragms and magnetic coils, like those shown in Weir, and now in extensive use.

The mounting means for the common stylus 95 may be differently constructed, as shown in the prior art patents mentioned (Heck, Emerson, Waters) using microphones rather than air cushions at the separately vibrating elements.

These and other changes and modifications 100 are contemplated by the invention as it is expressed in the appended claims.

What I claim is:

1. A duplex sound record having a sound track varying vertically for one sound record, 105 and varying horizontally for another sound record intelligibly related to the first record, means having a single sound track follower for simultaneously reproducing said two records, two electric circuits associated with said 110 means for carrying current in conformity with each record, means to vary the intensity of current out of proportion to the record, and means to reproduce sound from said two currents.

115 2. Means for reproducing sound comprising two intelligibly related sound records, electric means for picking up sound from each record, a single electric sound producer for said records, means to vary the strength 120 of sound reproduced from each record, and controllable means adapted to connect either one or both of said picking up means to said sound producer.

125 3. A duplex sound record having vibrations recorded vertically therein and vibrations recorded horizontally therein, and electrical pick-up devices for each record having a common stylus.

130 4. A duplex record having a track varying

- vertically for one record, and varying horizontally for another record intelligibly related to the first record, an electrical pick up system for each record, and means associated electrically with each system adapted to carry one stylus for the two records. 5
5. An electric pick-up device for recorded vibrations, comprising in combination a stylus-carrying body mounted for vibration vertically and horizontally, having a vertical plane and a horizontal plane, and an electrically sensitive body responsive to vibrations resting on each plane. 10
10. An electrical pick-up device for recorded vibrations comprising in combination means adapted to be moved by a stylus in two right-angular directions, and two microphone elements associated with said means to record vibrations in said directions. 15
20. An electrical pick-up device for recorded vibrations having a stylus carrier capable of vibration in right angular directions, an electric element influenced by motion of said carrier in one direction, and a second electric element influenced by motion of said carrier in the other direction, said elements being adapted to convert vibrations of the carrier into corresponding variations of electric current. 25
30. An electric pick-up device for phonograph records comprising two electrical elements for varying current by mechanical vibrations, a stylus carrier capable of vibrating in different directions for separately influencing said elements, means providing an electric circuit for each element, and current control means for each circuit. 35
40. An electric pick-up device comprising in combination a body having a stylus receptacle, mounting means for said body permitting vibrational movement in right angular directions substantially axially of a stylus in said receptacle and substantially transversely thereto, and two electrical microphone elements sensitive to vibrations of said body arranged with respect thereto to vary an electric current in each in accordance with said vibrations. 45
50. A duplex wave form record having vibrations recorded vertically therein and vibrations recorded horizontally therein, and electrical pick-up devices for each record having a common stylus. 55
55. A duplex wave form record having independent co-ordinated vibrations therein, one vertically and one horizontally, and electrical pick-up devices for each record having a common stylus. 60
60. Apparatus for tracing a wave form record in a groove comprising two independent electrical wave responsive tracing devices having a common stylus for said groove movable horizontally for one device and vertically for the other device. 65
65. A reproducing apparatus for phonographic sound records having vertical and horizontal variations for different records of the same sound, comprising in combination, means for carrying such a record, a reproducing unit positioned to reproduce vertical variations, and a reproducer positioned simultaneously to reproduce horizontal variations, and two sound producers for simultaneously presenting said two records binaurally to a human being. 70
75. 14. A reproducing apparatus for phonographic sound records having a single groove varying horizontally for one record and varying vertically for another record, comprising in combination, means for mounting a groove follower, independent vibratory means associated with said mounting means, one for lateral variations, and one for vertical variations, independent means for use with sound emitting means to be associated with each vibratory means, and sound emitting means arranged to present said two records binaurally to a human being. 80
85. 15. In combination a sound record having a sound track varying horizontally for sound primarily intended for one ear, and varying vertically for a binaurally related sound primarily intended for the other ear, binaurally instantaneous effects being coincident along the length of the track, means having a single sound track follower for separately reproducing the two records. 90
95. In testimony whereof I have hereunto affixed my signature. 100

CERTIFICATE OF CORRECTION.

Patent No. 1,855,151.

April 19, 1932.

W. BARTLETT JONES.

It is hereby certified that error appears in the printed specification of the above numbered patent requiring correction as follows: Page 3, line 74, claim 13, for "presently" read presenting; and that the said Letters Patent should be read with this correction therein that the same may conform to the record of the case in the Patent Office.

Signed and sealed this 12th day of July, A. D. 1932.
